UNITED STATES PATENT OFFICE.

BERT O. TILDEN, OF TRENTON, NEW JERSEY, ASSIGNOR TO B. O. T. MFG. CO., OF TRENTON, NEW JERSEY, A CORPORATION OF NEW JERSEY.

ATTACHMENT FOR FLUSH TANKS.

Application filed March 30, 1925. Serial No. 19,485.

To all whom it may concern:

Be it known that I, BERT O. TILDEN, a citizen of the United States, residing at Trenton, in the county of Mercer and State of New Jersey, have invented certain new and useful Improvements in Attachments for Flush Tanks, of which the following is a specification.

This invention relates to improvements in flush valve operating mechanisms, designed particularly for use in connection with vitrified china flush tanks, and has for its object to provide a fitting of the class, wherein all of the exposed parts are made of durable and ornamental vitrified material, which effectually conceal all of the metal connecting and supporting parts that usually extend beyond the tank. A particular object of the present invention is to provide a novel and simple china head-piece, which is supported by and conceals a portion of the valve-operating stem, and at the same time affords a novel support for the vitrified operating handle. A further object is to provide a head-piece, which is operated upon in the molding stage of its manufacture, for facilitating the connecting and securing of the related parts without requiring any machining or other work. And a further object is to provide a china head-piece, which is so constructed and applied to the metal parts of the fitting that, should the head-piece become broken or destroyed the metal operating parts may still perform their regular functions.

I attain these objects by the means set forth in the detailed description which follows, and as illustrated by the accompanying drawing, in which—

Figure 1 is a broken front side elevation of a flush tank to which my improvement is applied. Fig. 2 is a broken end elevation of the tank. Fig. 3 is a horizontal section taken centrally through the operating parts shown in Figs. 1 and 2. Fig. 4 is a front end view of the china head. Fig. 5 is a rear end view of the same. Fig. 6 is an enlarged central section taken on line 6 of Fig. 7. And Fig. 7 is an enlarged elevational view taken in the direction of the arrow in Fig. 6.

In the accompanying drawing, 2 represents a china flush tank of the usual construction, which preferably has its front face curved, as at 2' for strengthening and

ornamenting the tank. The flushing water may be supplied to the tank by any of the usual means (not shown). The filling of the tank may be controlled in the usual manner by a float 3, shown conventionally in Fig. 2. The emptying of the tank may be effected by any of the well-known flushing valve mechanisms, which it is not deemed necessary in the present case to show. The flush valve however, may be operated by means of a lift rod 4', which may be moved vertically by means of a lever 4, one end of which is preferably formed U-shaped for facilitating mounting the lever between perforated ears 5', of a bracket 5 which is mounted on the inner wall 2^a of the tank, as best seen in Figs. 2 and 3. The bracket 5 is formed with a tubular hub 5^a, which is shown inserted part-way into a molded opening 2^b, of the front wall of the tank, and forms together with a flange bushing 6 which is inserted from the outside of the tank, a bearing that supports a relatively long externally threaded sleeve 7, to which the bushing 6 is threaded. A nut 8 is applied to the projecting inner end of the sleeve 7, for rigidly clamping and holding the parts in place, as shown in Fig. 3. The lever 4 is rocked, for opening and closing the flush valve, by means of a relatively large loop 9, which is mounted on or may form a part of the inner end of a stem 9, the latter preferably passing through and being freely rotatable in the sleeve 7.

Outside of the tank, and beyond the bushing 6, is mounted a china escutcheon 10, the latter having a central opening to receive the sleeve 7. The bottom face of the escutcheon is preferably concave, as at 10', to receive and afford clearance for the flange of bushing 6. The reduced end of the escutcheon is formed with a relatively deep concentric cavity 10^a, into which the outer end of the sleeve 7 projects, and to this end of the sleeve is threaded a spanner-nut 12, for clamping the escutcheon against the outer face of the tank. The nut 12 only partially fills the socket 10^a and is preferably formed with a round face that fits ball-like into the socket 10', the stem 9 projects a considerable distance beyond the escutcheon and its outer end is inserted axially in a substantially globular head-piece 13, which is formed with a relatively deep

- socket 13' to receive the stem. At one side the head-piece is formed with a reduced cylindrical portion, as 13^a, and this portion is inserted loosely and axially in the 5 socket 10^a, and preferably lightly contacts with the outer face of the spanner nut 12, so as to avoid frictional wear and abrasion of the parts. The globular portion of the head-piece is formed with a circular socket, as 10 13^b and with a concentric opening 13^c, which connects the two sockets. 14 represents a vitrified handle, by which the flush valve operating mechanism is manipulated. One 15 end of the handle is formed with a molded axial socket, 14', in which is permanently embedded a metal connecting rod 15, in such manner that the free end of the rod, which is preferably threaded, may be inserted through the socket 13^b, and the opening 13^c, and thence into a transverse threaded hole 9^a of the stem, as best seen in Fig. 3. When assembling the handle and head-piece, a washer 16, preferably rubber or leather, is usually first inserted in the socket 20 25 13^b, so that when the handle is screwed up tight the china of the handle is insulated from the china head-piece 13, for preventing abrasion when the parts are tightened.
- By the construction and arrangement of 30 the parts, as described, there is an all-metal connection starting with the rod 15, throughout the train of parts, to the lift-rod 4'. This arrangement is provided for the purpose of enabling the users of the toilet to operate 35 the flush-valve, even though all of the china parts should be broken or destroyed, and it will also be understood that none of the movable china parts are allowed to make direct frictional contact with each other either, 40 during the assembling or the subsequent operations of the flushing mechanism.
- The head-piece 13 performs a valuable 45 and material function, in that it cooperates with the stem 9, for operatively supporting the handle 14, and also contributes greatly to the ornamental appearance of the exter-

nal parts of the fitting, since the handle, the head-piece, and the escutcheon are all made of china, and correspond with the vitrified tank 2, which is very desirable. 50

Having thus described my invention, what I claim, is:—

1. As a new article of manufacture, a head piece for the handles of flush valve operating mechanisms having stems for actuating the valve, including an integral globular vitrified body having a cylindrical neck projecting outwardly from a side of the body, said neck having a stem-receiving socket extending from its outer end into the body, the 60 body being formed with a recess in its periphery arranged in substantially the plane of the adjacent side of the neck and disposed at right angles to the socket and being further formed with an opening extending from 65 the recess into the socket.

2. A head piece for the handles of flush valve operating mechanisms having stems for actuating the valve, including an integral globular vitrified body having a cylindrical neck projecting outwardly from a side of the body, said neck having a stem-receiving socket extending from its outer end into the body, the body being formed with a recess in its periphery arranged in 70 substantially the plane of the adjacent side of the neck and disposed at right angles to the socket and being further formed with an opening extending from the recess into the socket, and an escutcheon for the head-piece including a circular body having a central axial opening and having a concentric socket at one end to receive the neck of the head piece, the bottom wall of the socket being concave, the opposite end of the body 75 being formed with a circular cavity surrounded by an annular face which latter is concaved to conformably seat against the convex outer face of a flush tank. 80 85

In testimony whereof I affix my signature.

BERT O. TILDEN.
